United States Patent Office.

JOHN GOLDING, OF NEW YORK, N. Y.

Letters Patent No. 67,039, dated July 23, 1867.

IMPROVED LIFE-PRESERVING MATTRESS AND RAFT.

The Schedule referred to in these Letters Patent and making part of the same.

TO ALL WHOM IT MAY CONCERN:

Be it known that I, JOHN GOLDING, of the city, county, and State of New York, have invented a new and useful improved Life-Preserving Mattress and Raft; and I do hereby declare the following to be a full, clear, and exact description of the same, reference being had to the accompanying drawings, forming part of this specification, and in which—

Figure 1 is a perspective view of my invention.

Figure 2 is a cross-section of the same, through the body of the chest B.

Figure 3 is a cross-section of the same through the compartment C.

Similar letters of reference indicate corresponding parts in the several figures.

In this invention the mattresses used in the berths of ships are a combination of the common mattress and a raft or float, the latter provided with apartments and vessels for containing food, water, &c., and the whole articles thus made being provided with means by which any number of them can be instantly attached together.

The invention particularly consists in the construction of a box or chest under the mattress-bed, to which the latter is attached, having compartments for containing food, &c., and being provided with snap-hooks and eyes, or loops, whereby a number of mattresses can be instantaneously connected into one floating structure, upon which a number of persons can find temporary support in case of shipwreck.

In order that others skilled in the art to which my invention appertains to make and use the same, I will proceed to describe it in detail.

In the drawings, A represents the mattress-bed, which may be filled with any suitable material, and B represents a chest or box, in width and length corresponding to the bed, and of suitable depth, upon the top of which the bed lies, and to which it is attached, the whole, thus constructed, forming the mattress that is used in the berths of the ship. C is a compartment in one end of the chest B, having suitable openings, and means of closing them water-tight, as shown at c c'. Any required number of these compartments may be made in the box. The mattress-bed must be so affixed to the box over the compartment C that it may be lifted in order to allow of the opening of the compartment for the purpose of putting in or taking out the provisions. D D' are snap-hooks and eyes firmly attached to the box B, by which any number of boxes may be instantly fastened together into one raft. Instead of snap-hooks and eyes, any other mode of fastening may be adopted which may be found to answer the purpose as well, as, for instance, spring-bolts, with corresponding perforated plates for receiving the ends of the bolts, &c. The box B is constructed of strips or blocks of cork, properly fastened together by pins or metallic or wooden straps, or any other suitable means, so as to form an exceedingly light and yet strong water-tight chest. It may then be covered with cloth or ticking, which will better adapt it for every-day use in the berth. The whole thus constructed, and with the bed attached, forms a light and convenient mattress for common use.

I do not claim connecting mattresses for the purpose of making floats, or providing them with devices for allowing such a connection, as I am aware that loops are already secured to mattresses to allow the uniting of the same by means of ropes or strings.

Having thus described my invention, what I claim as new, and desire to secure by Letters Patent, is—

The combination of the mattress-bed A with the floating box B, the latter having the compartments C C, and being constructed of cork as described, and provided with snap-hooks and eyes, or their equivalents, the whole being constructed and arranged substantially as and for the purpose specified.

To the above specification of my improvement I have signed my hand this 23d day of May, 1867.

JOHN GOLDING.
